United States Patent Office

Des. 190,999
Patented Aug. 1, 1961

190,999

TOY CHEST

Fred A. Mykleby, 6658 Ben Ave.,
North Hollywood, Calif.

Filed May 27, 1960, Ser. No. 60,750

Term of patent 14 years

(Cl. D34—15)

FIG. 1 is a perspective view of a toy chest showing my new design;

FIG. 2 is a side elevational view;

FIG. 3 is one end elevational view;

FIG. 4 is another end elevational view; and

FIG. 5 is a top plan view.

I claim:

The ornamental design for a toy chest, as shown.
